CLAIM

We claim the ornamental design for a grooming tool handle, as shown and described.

DESCRIPTION

FIG. 1 is a perspective view of a grooming tool handle;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken line portions are not claimed. Furthermore, the boundary of the start of the unclaimed portion on the handle is indicated by the end of the extent of the shade lines on the upper portion of the handle.
